ALFRED P. BAMBERGER AND WINTFIELD SCOTT GUISTWHITE, OF NEW CUMBERLAND,
PENNSYLVANIA, ASSIGNEES OF ONE-THIRD TO BENJAMIN F. GARVER, OF NEW
CUMBERLAND, PENNSYLVANIA.

ROOFING.

1,107,568.

Specification of Letters Patent. Patented Aug. 18, 1914.

Application filed November 6, 1913. Serial No. 799,496.

To all whom it may concern:

Be it known that we, ALFRED P. BAMBERGER and WINTFIELD S. GUISTWHITE, citizens of the United States of America, and 5 residents of New Cumberland, Cumberland county, State of Pennsylvania, have invented certain new and useful Improvements in Roofing, of which the following is a specification.

10 This invention relates to certain new and useful improvements in roofing and it has for its objects among others to provide an improved simplified form of roofing which shall be durable, in which the securing means 15 will be hidden from view except at the edge of the roof.

It has for a further object to provide means for securing the roofing material in such a manner as to insure against its being 20 easily removed by the wind and in which the joints shall be so formed and protected as to prevent all liability of leakage by the rain being driven in between the joints.

Other objects and advantages of the invention will hereinafter appear and the 25 novel features thereof will be particularly pointed out in the appended claims.

The invention is clearly illustrated in the accompanying drawings, which, with the 30 numerals of reference marked thereon, form a part of this specification, and in which—

Figure 1 is a perspective view with portions broken away showing the portions of a roof covered in accordance with our present invention. Fig. 2 is a section on the line 2—2 of Fig. 1 looking in the direction of the arrows. Fig. 3 is a section on the line 3—3 of Fig. 1, looking in the direction of the arrows. Fig. 4 is an enlarged section through one of the joints, portions being 35 broken away. Fig. 5 is an enlarged fragmentary perspective view showing the hooks of the interengaging parts.

Like numerals of reference indicate like 40 parts throughout the different views.

Referring to the drawings, 1 designates the sheathing or boarding of the roof of usual construction. The roof covering may be of any suitable material adapted to the 45 purpose, preferably lead, which may be rolled very thin and which will never rust, nor does it require to be painted. The sheets may be of any desired size and while they may be arranged horizontally, vertically or 50 diagonally across the roof, in the present

instance we have chosen to show the same as extending upwardly, or in other words, from the comb of the roof to the eaves. These sheets 2 are secured in position in the following manner. 3 are fasteners, preferably of tin, although they may be other material, having a portion 4 adapted to lie flat against the roof 1 where it is secured by a nail or nails or the like 5, as seen clearly in Fig. 4. This fastener has its free edge bent 60 upon itself to form a hook 6, there being an offset 7, as seen in Fig. 4, for a purpose which will be obvious. Into this hook, the adjacent edge of one of the strips 2 is designed to be hooked, as seen at 8, and the 65 adjacent overlapping edge of the next adjacent sheet or strip 2 of the lead or other outer covering is also engaged within this hook of the fastener and also engaged in the hook 8 of the first-named sheet 2, as seen at 70 9 in Fig. 4. The fasteners 3 are then hammered down tightly and then nailed fast to the roofing boards at the other side of the hook, that is through the member 4, as shown, by the nails 5 or other suitable fastening means. After a course is nailed, the sheet 2 is pulled over the portion 4 of the fastener, as seen in Fig. 4, and is ready for another course, and the operation is repeated 75 until the whole roof is covered, each fastener 80 being tightly hammered down to secure the overlapped edges of the two adjacent sheets 85 firmly in position. A roof thus covered will most effectually guard against leakage and the securing means are entirely concealed 90 and protected against the elements. The side and bottom edges of the sheets 2 may be fastened by nails or the like 10 at the lower edge of the roof and by suitable means as the 95 nails or the like 11 at the edges, as seen in Fig. 1.

If desired, the edges of the sheets 2 at the sides of the roof may be secured by the hooked members 12, as seen in Fig. 2, the outer edges of the material 2 being inserted 100 between the jaws of the hooked members 12 and then hammered down tightly, nails or the like 11 holding the hooked members in position.

At opposite edges of the roof we may employ strips 13, preferably of tin or the like, secured to the board 1 by nails or other means, for the purpose of slightly raising the outer covering 2 at these points to keep the water from running over the edges. If 110

desired, the lower edges of the covering material 2 may be likewise held firmly between hooked members 15 secured to the lower edge of the boarding 1, as seen in Fig. 3, 5 and, if necessary, this edge may be slightly raised by a strip 16, as seen in said Fig. 3.

Roofing material secured in accordance with the above invention is firmly held in place, the joints are such as to absolutely 10 prevent leakage and water is prevented from running over the edges, while at the same time the material is caused to snugly hug the roofing boards and as the edges are all secured firmly in position, there is 15 practically no likelihood of the roof being taken off by the wind. Importance is attached to the fact that the fastener and the sheet be turned up to furnish shoulders against which the edge of the adjacent sheet 20 abuts and that the edge of the adjacent sheet be bent over and both the fastener and the first sheet hooked into such turned-over portion.

What is claimed as new is:—

In a roof, a fastening member having a 25 portion parallel with the roof and secured directly to the upper face thereof, said member having its free edge bent upon itself to form a hook, a covering strip and an adjacent covering strip, the first-named strip 30 and the fastener being turned up to form shoulders against which the edge of the adjacent covering strip abuts and the edge of the adjacent sheet bent over and the fastener and the first-named sheet having interlocking portions, the interlocked portions of the fastening member and said covering strips being compressed substantially parallel with the roof. 35

Signed by us at New Cumberland, Pa. this 27th day of October, 1913.

ALFRED P. BAMBERGER.
WINTFIELD SCOTT GUISTWHITE.
